UNITED STATES PATENT OFFICE

2,588,193

SPINNING AND TWISTING RING

George F. Albrecht, Saco, Maine

Application August 16, 1950, Serial No. 179,797

17 Claims. (Cl. 57—120)

1

This invention pertains to spinning and twisting rings such as are employed in ring-spinning and similar frames in the production of textile yarn or thread and relates more especially to a ring assembly of the self-lubricating type wherein the traveler guiding annulus is of porous, oil-absorbent material, for example as disclosed in my prior Patent No. 2,084,756 dated June 22, 1937. In my later Patent No. 2,502,116, dated March 28, 1950, I have shown such a porous oil-absorbent ring mounted in a support or holder shaped to provide an annular oil reservoir designed to furnish a continuous supply of oil to the porous ring. This arrangement is highly efficient and makes hand oiling of the ring wholly unnecessary. However, because the ring is thus better lubricated than by hand oiling, it has been found that when a broken yarn end (yarn breaks being a common occurrence in the spinning operation) contacts the inner surface of the traveler guiding ring (as the broken end may do before the frame tender observes and pieces up the broken yarn) it absorbs oil and dust from the inner surface of the ring and transfers this oil or discoloration to the yarn on the bobbin so that the yarn on the bobbin can no longer be classed as a first grade product.

The present invention has for an object the prevention of oily or dirty yarn when using an oil-absorbent traveler guiding ring such as above referred to. A further object is to provide an improved ring assembly wherein the traveler guiding ring is of oil-absorbent material but has associated therewith a shield or guard which is operative to prevent contact of a yarn end with the oily surface of the ring. A further object is to provide a ring assembly wherein a porous, oil-absorbent ring is constantly fed with oil from a reservoir and wherein the inner surface of the oil-absorbent ring, below its traveler-contacting portion, is lined with material which is not oil-absorbent. A further object is to provide a ring assembly wherein a porous, oil-absorbent ring is closely confined between concentric walls of an oil-impervious holder or support, the inner wall, at least, of said support being of an organic material which conveys oil by capillary action at a relatively slow rate as compared with brass, for example. A further object is to provide a ring assembly wherein an oil-absorbent ring is mounted in an annular holder of oil-impervious material, the opposed surfaces of the ring and holder being shaped to define an annular oil reservoir and having means accessible from the outer side of the ring for delivering oil to the reservoir. A further object is to provide a ring assembly in which a traveler-guiding ring is mounted in a holder of oil-impervious material and has associated therewith an annular shield or guide disposed within the holder and spaced from the

traveller-guiding ring to prevent contact of a broken yarn end with the lubricated surface of the ring. Other and further objects and advantages of the invention will be pointed out in the following more detailed description and by reference to the accompanying drawings wherein

Fig. 1 is a plan view of a ring assembly embodying the present invention, the assembly being shown mounted upon the top rail of a spinning frame, said top rail being broken away;

Fig. 2 is a side elevation, to larger scale, of the ring assembly of Fig. 1, shown separate from the rail;

Fig. 3 is a diametrical section, to still larger scale, substantially on the line 3—3 of Fig. 1 but omitting the ring rail;

Fig. 4 is a diametrical section of the traveler-guiding ring alone;

Fig. 5 is a fragmentary radial section through the traveler guiding ring and a support therefor in accordance with another embodiment of the invention;

Fig. 6 is a view similar to Fig. 5, but illustrating a further modification; and

Fig. 7 is another fragmentary radial section similar to Fig. 5 but illustrating a still further modification.

Referring to the drawings, the numeral 10 indicates a portion of the ring rail of a spinning or twisting frame of conventional type, this ring rail supporting the novel ring assembly of the present invention. This ring assembly comprises the supporting annulus or holder 11 and the traveler guiding annulus or ring 12. In accordance with a preferred construction, the traveler guiding ring 12 is of the oil-absorbent type, for example such as disclosed in my above-named patents. Thus, this ring 12 consists throughout of a material which is hard and durable enough to withstand the wear of the moving traveler and which is capable of taking and maintaining a visually smooth and even polished surface finish so as to reduce the friction between it and the traveler to a minimum. On the other hand, the traveler guiding ring element 12 is porous, comprising throughout its entire substance a multitude of minute capillary canals and cavities so small as to be visible only with the assistance of a microscope and which are distributed throughout the material with substantial uniformity. This ring may be of any suitable substance, having the above characteristics. For instance it may be one of the synthetic resins rendered suitably porous in the final moulding operation, by procedures known to those skilled in the art. At present, however, it appears that certain metallic compositions or alloys are preferable, for instance compositions prepared from powdered metal, iron, copper, etc., together with graphite, and highly compressed and sintered. Such an

alloy may, for example, be prepared by incorporating 90 parts by weight of copper and 10 parts of tin with 6 parts of graphite and 2 parts of salicylic acid, all in a very finely divided state, the ingredients being thoroughly mixed and then briquetted under high pressure to produce a ring of substantially the desired dimensions. The briquetting pressure is desirably of the order of 75,000 pounds per square inch. After briquetting the rings are sintered in a non-oxidizing atmosphere for approximately three hours at a temperature of the order of 1425° F. After removal from the sintering boxes, the rings are surfaced and sized, for example by the use of concentric arbor and die members which squeeze and reduce the material of the ring to substantially the final desired dimensions.

The result of this procedure is to provide a ring which in its entirety is porous and capable of slowly transmitting a lubricating medium such as oil from one point to another. The microscopic structure of the ring may be likened to that of a fine sponge, and comprises a multitude of minute cells or canals generally communicating with one another and having walls of a bronze-like alloy. The cells which are exposed at the outer surface of the ring are in most instances open at such outer surface, although the ring is superficially solid, and except under the microscope, its surface shows no indication of these open cells or pores.

The ring thus devised acts as a capillary barrier, when interposed in the path of fluid, for example lubricating oil, cutting down the velocity of flow to a rate which, within wide limits, is substantially independent of the fluid pressure head so that so long as fluid is supplied to one side of this porous barrier, the rate of delivery from one side to the other will be substantially uniform, regardless of fluctuations in the supply head.

The two annuli are arranged in concentric relation, the traveler guiding ring 12 being mounted upon the supporting annulus or holder 11, the latter having slotted ears or lugs L (Fig. 1) which receive screws S by means of which the ring assembly is attached to the ring rail 10.

Referring particularly to Fig. 4, the traveler guiding ring or annulus 12 comprises a body portion 13 having a cylindrical inner surface 14, a cylindrical outer surface 15 concentric with the surface 14, a flat bottom surface 16 and a T-shaped upper portion or head 17 having inner and outer guiding surfaces 18 and 19 for guiding a traveler of C-shape such as illustrated in Fig. 3. Preferably, to reduce weight and cost, the upper portion of the body of this ring is reduced in radial thickness as shown at 20, the configuration of the outer surface of the ring preferably being such as to provide a horizontal face 20a, while its lower, outer edge is beveled or recessed as shown at 21.

The supporting annulus 11, as shown more particularly in Fig. 3, is of sheet material, for example metal and of substantially U-shape in radial section, comprising the outer vertical wall 22, the inner vertical wall 23 concentric with the outer wall and the substantially horizontal bottom wall 24, the walls 22 and 23 being so spaced apart radially as to provide a channel designed to receive the body portion of the traveler guiding ring with an oil-tight, press fit. The inner surface 14 of the ring 12 fits tightly against the inner surface of the wall 23 of the supporting annulus and the outer cylindrical surface 15

of the ring 12 fits snugly against the inner surface of the outer wall 22 of the supporting annulus. When the parts are assembled the flat bottom surface 16 of the traveler guiding ring rests firmly against the bottom 24 of the supporting annulus. When thus assembled the recess 21 at the outer lower corner of the traveler guiding ring cooperates with the walls 22 and 24 of the supporting annulus to form an annulus oil-receiving channel 25 (Fig. 3) which is enclosed at all sides so as to exclude dust and lint, and so as to prevent any possibility of entrance of a broken yarn end into the body of oil in said channel.

Preferably the supporting annulus 11 is provided with an integral, outstanding boss 26 which is hollow to provide a reservoir R (Fig. 3) for the reception of a supply of lubricant. A hinged cover 27 normally forms a closure for the reservoir R. The wall 22 of the supporting annulus has an opening 28 (Fig. 3) through which lubricant from the reservoir R may pass into the channel 25. With this arrangement, the oil supply to the ring 12 is automatic; the oil for lubricating is easily placed in the reservoir which is at the exterior of the ring assembly; and oil from the reservoir flows inwardly from the reservoir to the channel 25. The upper edges 29 and 30 of the walls 22 and 24 are preferably at substantially the same level, the edge 30 being a sufficient distance below the guiding surface 18 to provide clearance for the traveler C. However, the inner wall 23 forms a lining for the oil-absorbent traveler guiding ring and since the wall 23 is of oil-impervious material it prevents oil from exuding to the interior of the ring assembly so that broken yarn ends, extending down into the interior of the ring assembly, do not come into direct contact with the oil-absorbent traveler guiding ring.

While the supporting annulus may, as above described, be of metal, it is found that certain other materials have especially appropriate characteristics for this particular use, that is to say, to act as a shield between the oil-absorbent ring and the broken yarn ends. Thus, for example, it has been found that certain synthetic resins which are unaffected by the lubricating oil and which are not subject to atmospheric corrosion are less prone to convey oil by capillary action than are the commoner metals. Thus, such a plastic, when employed in the guard element of the interior of the ring assembly, appears to inhibit rapid capillary travel of oil from the oil-absorbent ring downwardly over the upper edge 30 to the interior surface of the wall 23. Among the plastics appropriate for the purpose may be mentioned polystyrene; acrylic acid polymers; and vinyl ester copolymers, characterized by toughness, resilience and shock resistance; resistance to corrosion, and which are hard and shape retaining at normal temperatures.

In the arrangement shown in Fig. 5 the supporting annulus is shown as a casting 11a having the substantially horizontal upper surface 30 which forms a support for the lower surface 16 of the traveler-guiding ring. In this arrangement the traveler-guiding ring is not provided with the recess 21 at its lower outer edge but the upper face 30 of the supporting annulus 11a is provided with a groove 33 which, when the parts are assembled, provides the annular channel for lubricant. The outer edge of the horizontal face 30 is defined by an upstanding cylindrical wall 31 of such internal diameter that when

the parts are assembled the outer surface 15 of the traveler-guiding assembly forms a leak-tight press fit with the wall 31. To prevent leakage between the lower surface of the traveler-guiding assembly and the surface 30 of the supporting annulus, suitable cement 32 may be interposed between these parts before assembling. If the parts are of metal, this cement may be in the nature of solder or other means for providing a molecular union.

In this arrangement the yarn protecting liner is an independent cylindrical ring 34 which fits snugly within the traveler guiding ring, for example with a press fit, or it may be secured by means of cement or equivalent material. Preferably this guard ring 34 is of a synthetic resin having the characteristics above referred to.

In the arrangement shown in Fig. 6 the supporting annulus 11^b is a molded body of material, for example synthetic plastic, shaped to provide the outer cylindrical wall 35 and the inner cylindrical wall 36 which are spaced apart to provide a channel in which the body portion of the traveler guiding ring is assembled with a press fit or other provision to prevent oil leakage between the parts. In this arrangement the traveler guiding ring is shown as having a recess which, in association with the supporting annulus, provides the annular oil channel 25. In this arrangement the upper edge of the wall 35 is substantially flush with the horizontal surface 20^a of the traveler guiding ring, while the upper edge 37 of the inner wall 36 extends up to a point such as to provide just sufficient clearance for the traveler as the latter revolves about the ring. In this arrangement, wherein the entire supporting annulus is of a synthetic resin, the impervious inner wall 36 constitutes a guard to prevent contact of the yarn end with the oil-absorbent guiding ring.

In the arrangement of Fig. 7, the supporting annulus is in general like that shown in Fig. 3, being of sheet metal and comprising the outer cylindrical wall 38, the inner cylindrical wall 39 and the horizontal bottom wall 40, the walls 38 and 39 being spaced to permit the body portion of the traveler guiding ring to be entered between them with an oil-tight fit. In this arrangement the upper margin of the wall 38 is bent inwardly as shown at 41, to overlie the horizontal face 20^a of the traveler guiding ring, thus holding the parts in permanently assembled relation. In this arrangement the guard for preventing contact of the yarn end with the traveler guiding ring consists of an independent member, preferably of synthetic resin, having the characteristics above described and including the cylindrical portion 42, of such depth that its upper edge 43 lies substantially in the horizontal plane of the upper edge of the head portion 17 of the traveler guiding ring. This guard member also comprises the outwardly directed horizontal flange 44 whose outer edge fits snugly against the inner surface of the wall 39 of the supporting annulus. With this arrangement the part 42 constitutes the guard. It is spaced radially inward from the wall 39, and since it extends throughout the entire vertical height of the ring assembly it is very effective in preventing contact of the yarn end with any oil-impregnated or oil-coated portion of the ring assembly.

While certain desirable embodiments of the invention have herein been illustrated and described by way of example, it is to be under-

stood that the invention is broadly inclusive of any and all modifications falling within the scope of the appended claims.

I claim:

- 5 1. A spinning ring assembly comprising two coaxial annuli, one of said annuli being a traveler guiding ring of oil-absorbent material and the other annulus being a supporting ring shaped to define an annular channel having substantially 10 cylindrical, radially spaced, concentric walls, the traveler guiding ring comprising a body portion having a bottom surface and coaxial, peripheral outer and inner surfaces, said body portion fitting snugly and oil-tight between the outer and inner 15 concentric walls of the supporting ring, the body portion of the traveler guiding ring having a recess at the intersection of its bottom surface with its outer peripheral surface, said recess defining an annular channel for the reception of lubricant, 20 and a reservoir for lubricant at the exterior of the supporting annulus, a passage leading from the reservoir through the outer wall of the supporting annulus to said annular channel.
2. A spinning ring assembly according to claim 25 1, further characterized in that the supporting annulus is of sheet material and substantially U-shaped in radial section, its outer and inner concentric walls being of substantially the same height, the bottom surface of the traveler guiding 30 ring being substantially flat and seating upon the bottom of the channel in the supporting ring.
3. A spinning ring assembly comprising two coaxial annuli, one of said annuli being a traveler guiding ring of the oil-absorbent type and 35 the other annulus being a supporting ring of oil-impervious material, the traveler guiding ring comprising a body portion having inner and outer concentric cylindrical surfaces and an annular bottom surface, opposed surfaces of the 40 supporting annulus and traveler-guiding ring being shaped to provide an annular, concealed channel for the reception of lubricant, the supporting annulus having an annular upstanding wall which contacts said outer cylindrical 45 surface of the traveler guiding ring with an oil-tight fit, the supporting annulus having a passage leading from its exterior to said channel for delivering lubricant to said channel, and a liner ring of oil-impervious material arranged 50 within and concentric with said inner cylindrical surface of the traveler guiding ring and which is operative to prevent contact of yarn with the oil-absorbent traveler guiding ring.
4. A spinning ring assembly according to claim 55 3, further characterized in that the liner element is of an organic material which is non-absorbent of oil and substantially unaffected by exposure to lubricating media or atmospheric air.
5. A spinning ring assembly according to claim 60 3, further characterized in that the liner element is a synthetic resin which is hard, tough, and shape-retaining, and which is not affected by atmospheric moisture or gases.
6. A spinning ring assembly according to claim 65 3, further characterized in that the lining element is integral with the supporting annulus.
7. A spinning ring assembly according to claim 3, further characterized in that the lining element is integral with the supporting annulus and together with the upright wall of the latter defines an annular channel, and body portion of the traveler guiding ring seating in said channel with a press fit between said wall and the liner element.
8. A spinning ring assembly as set forth in

7
claim 3, further characterized in that the liner element is integral with the supporting annulus and together with the upstanding wall of the latter defines an annular channel, the body portion of the traveler guiding ring fitting leak-tight within said channel, the body portion of the traveler guiding ring having a recess at the intersection of its bottom surface and its outer cylindrical wall to form the annular oil-receiving channel.

9. A spinning ring assembly according to claim 3, further characterized in that the liner is spaced inwardly from the inner surface of the body portion of the traveler guiding annulus and extends up substantially to the plane of the upper edge of the traveler guiding annulus.

10. A ring assembly as set forth in claim 3, further characterized in that the liner is substantially L-shaped in radial section comprising a horizontal flange and a cylindrical wall, the outer edge of the flange engaging and being fixed to the supporting annulus and the cylindrical portion of the liner being spaced from the inner surface of the traveler guiding annulus.

11. A spinning ring assembly comprising a traveler guiding annulus having a body portion having cylindrical, concentric inner and outer surfaces and a flat bottom surface, and an annular holder of oil-impervious material having a horizontal upper surface on which rests the flat bottom surface of the traveler guiding annulus, the outer edge of the horizontal surface of the holder being defined by an upstanding wall whose inner surface contacts the outer cylindrical surface of the body portion of the traveler guiding annulus, and a liner of synthetic plastic which does not readily conduct oil by capillary action.

12. A spinning ring assembly comprising a traveler guiding annulus having a body portion having cylindrical, concentric inner and outer surfaces and a bottom surface and an annular holder having a horizontal surface on which rests the bottom surface of the traveler guiding annulus, the holder comprising means for keeping the traveler guiding annulus in concentric relation to the holder, and a cylindrical guard, independent of the holder, arranged within the traveler guiding annulus and which is operative to prevent contact of a broken yarn end with the oily inner surface of the traveler guiding annulus.

13. A spinning ring assembly comprising a traveler guiding annulus having a body portion having cylindrical, concentric inner and outer surfaces and a unitary holder of organic material having an annular channel within which the body portion of the traveler guiding annulus fits snugly, said channel being defined by inner and outer concentric walls, the inner of said walls extending up substantially to the traveler guiding surface of the traveler guiding annulus and constituting a shield to prevent contact of a broken yarn end with the oily inner surface of the traveler guiding annulus.

14. A spinning ring assembly comprising a traveler guiding annulus having a body portion having cylindrical, concentric inner and outer surfaces and a holder for the traveler guiding annulus, said holder being of an oil-impervious material and having radially spaced, concentric, cylindrical walls defining an annular channel

5 within which the body of the traveler guiding annulus fits snugly, the outer of said cylindrical walls having an inwardly directed flange which overlaps the body portion of the traveler guiding annulus and permanently keeps the holder and annulus in assembled relation, and an annular cylindrical shield of organic material concentric with and spaced radially inwardly from the inner wall of the holder, said shield reaching up substantially to the plane of the upper edge of the traveler guiding annulus, the shield having a radial flange which contacts and is secured to the inner surface of the inner wall of the holder.

15. A spinning ring assembly comprising a traveler guiding ring of the oil absorbent type, said ring having a body portion provided with inner and outer concentric, cylindrical surfaces and having a substantially flat annular bottom surface, oil-impervious annular wall elements 15 snugly contacting the inner and outer cylindrical surfaces respectively of the traveler guiding ring, the outer at least of said annular wall elements being integral with a part which contacts the bottom surface of the traveler guiding ring, there being an annular channel concentric with the 20 traveler guiding ring adjacent to the junction of the bottom surface of the traveler guiding ring with the outer of said cylindrical wall elements, and means for supplying lubricant to said channel, the upper edge of said inner impervious wall 25 element being spaced below the upper edge of the traveler guiding ring a distance just sufficient to provide clearance for the traveler.

16. A spinning ring assembly comprising a traveler guiding ring having a body portion provided with inner and outer concentric cylindrical surfaces and an annular bottom surface, spaced concentric cylindrical wall elements between which the body portion of the traveler guiding ring is arranged and which contact the cylindrical inner and outer surfaces of the traveler guiding ring with an oil-tight fit, the upper edge of the inner of said cylindrical wall elements being spaced below the upper edge of the traveler guiding ring a distance just sufficient to provide clearance for the traveler, and means for supplying lubricant to the traveler guiding ring.

17. A spinning ring assembly comprising a traveler guiding ring of oil absorbent type, means for supporting the traveler guiding ring and for supplying lubricant to said ring at a point near its outer periphery, the ring having a cylindrical inner surface and an annular wall element of impervious material fitting snugly against the cylindrical inner surface of the traveler guiding ring, said annular wall element extending upwardly from the bottom of the traveler guiding ring and terminating below the top of the traveler guiding ring a distance just sufficient to provide clearance for the traveler.
